CHARLES REISTLE, OF BROOKLYN, NEW YORK.

Letters Patent No. 87,201, dated February 23, 1869.

IMPROVED MOLASSES-PITCHER.

The Schedule referred to in these Letters Patent and making part of the same.

To all whom it may concern:

Be it known that I, CHARLES REISTLE, of Brooklyn, county of Kings, State of New York, have invented a new and improved Molasses-Pitcher; and I do hereby declare that the following is a full, clear, and exact description thereof, which will enable those skilled in the art to make and use the same, reference being had to the accompanying drawing, forming part of this specification, in which drawing—

Figure 1 represents a vertical central section of this invention.

Figure 2 is a plan or top view of the same.

Similar letters indicate corresponding parts.

This invention consists of the arrangement of an inclined tube, open at both ends, and extending from the spout of a molasses-pitcher into its interior, in such a manner that the drop which, in pouring molasses from the pitcher, invariably adheres to the spout, and usually runs down on the exterior of the pitcher, is sucked in through said tube, and returned to the interior of the pitcher as soon as the pitcher is brought in an upright position.

A represents a molasses-pitcher, made of metal, clay, or glass, or any other suitable material.

This pitcher is provided with a spout, C, and with a tube, B, which extends, in a slightly-inclined position, from the spout to the interior of the pitcher, as shown in fig. 1 of the drawing.

The tube B has a perforation, b, at or about the middle of its length, in order to assist in the admission of air into the tube, which is necessary in consequence of the thickness of the molasses which flows through it.

It is supported by the top-piece c of the front wall of the pitcher, which piece remains after the pitcher is cut out to form the opening which leads to the spout.

Its forward end terminates at the top of the spout C, just above a ledge, D, communicating therewith.

This ledge projects upward and outward, so that the drop of molasses is guided at once to the tube.

When molasses is poured out of the pitcher, and the pitcher is returned to an upright position, a drop adheres to the spout, and, in ordinary pitchers, this drop runs down at the outside of the pitcher, and soils the same, and also the table-cloth on which the pitcher stands.

This difficulty is overcome by the application of the tube B.

If my pitcher is returned to an upright position after some of its contents have been poured out, the drop adhering to the spout is sucked in through said tube, and prevented from soiling the exterior of the pitcher or the table-cloth.

A lip, or projection, a, at the inner end of the tube B, assists in carrying the drop back into the pitcher without fail.

I do not wish to undertake the explanation of this action on scientific principles, and I will merely state that in a very large number of experiments made with my pitcher, it never failed to draw in the drop, and the exterior of the pitcher can thus be kept clean without trouble.

Having thus described my invention,

What I claim as new, and desire to secure by Letters Patent, is—

The curved outwardly-projecting ledge D, on the spout C, in combination with the single tube B, communicating therewith, said tube being supported upon said spout and the front-wall partition c, and provided with opening b, when the parts are constructed and adapted to operate as herein represented and described, and for the purpose specified.

This specification signed by me, this 15th day of January, 1868.
